STEAMING AND PRESSING FLATIRON

Harry L. Gordon, Sunland, Calif.

Application May 29, 1950, Serial No. 164,874

5 Claims. (Cl. 38—77)

1

My invention relates to steaming and pressing flatirons of the type adapted for use by tailors and in pressing establishments as distinguished from the domestic flatiron.

It is a purpose of my invention to provide a steaming and pressing flatiron which is adapted for flexible connection to a remote source of steam to receive steam therefrom while in use, and so that such steam can be discharged directly onto a fabric being ironed, and which has therein an electrical heating element so associated with the course of travel of the steam through the flatiron as to superheat the steam in transit, thus permitting the application of such superheated steam to a fabric in the steaming and pressing thereof.

A number of advantages stem from the use of superheated steam in the steaming and pressing of fabrics as against the use of steam at ordinary temperatures. It is relatively dry, and, therefore, does not unnecessarily dampen the cloth or other fabric being ironed beyond what is actually required to effect thorough pressing thereof. Further, it permits a fabric to be pressed more rapidly than heretofore, and practically no moisture is left in the fabric. Particularly in the case of clothing is the garment left dry and ready for wear, and without losing the creases pressed therein as is the case with a damp pressed garment.

It is also a purpose of my invention to provide a flatiron of the character above described which embodies an upper body and a lower body, the latter having an apertured sole plate from which the superheated steam is discharged onto the fabric being ironed. In the upper body is contained a steam chamber for receiving the steam from the source, and a passage leading from this chamber to the bottom of the body for discharging the steam from the apertures in the sole plate. The electrical heating element is also carried by the upper body and is positioned about a passage and beneath the steam chamber to effect the afore described superheating of the steam traversing the two.

To avoid scorching or burning of any fabric being ironed resultant of inadvertently leaving the flat iron on the fabric without disrupting the supply of current to the electrical heating element, my flat iron is constructed to operate in the manner of the flat iron disclosed in my copending, now abandoned application No. 752,105, filed June 3, 1947. That is to say, the upper body of my present flat iron is vertically movable to occupy lowered and elevated positions therein.

In the lowered position the electrical heating element is contiguous to the sole plate of the lower body so that the maximum heat of the element is transmitted to the sole plate for iron-

ing. In the elevated position of the element it is sufficiently spaced from the sole plate to prevent the latter from scorching or burning any fabric upon which it rests.

In the flatiron of my aforesaid application, springs are located in the lower body for urging the upper body to elevated position so that manual pressure downward on the upper body is required to move it to a lowered position. In my present flatiron I again employ springs, but instead of them being within the lower body where they are subject to the intense heat of the heating element, causing them soon to lose their tension, I locate the springs exteriorly of both bodies and remotely from the heating element as well as from the steam chamber of the upper body. As a consequence, the springs are not subjected to the maximum heat of either the heating element or the steam within the chamber, and, therefore, their tension is preserved to successfully urge the upper body to elevated position once it is relieved of downward pressure.

I will describe only one form of flatiron embodying my invention, and will then point out the novel features thereof in claims.

2 In the accompanying drawings:

Fig. 1 is a view showing in perspective one form of flatiron embodying my invention.

Fig. 2 is a vertical sectional view taken on the line 2—2 of Fig. 4, and showing the upper body in lowered position within the lower body.

Fig. 3 is a view similar to Fig. 2 showing the upper body in elevated position in the lower body.

Fig. 4 is a top plan view of the flatiron with a portion thereof broken away.

Fig. 5 is a transverse sectional view taken on the line 5—5 of Fig. 4.

Fig. 6 is a fragmentary vertical sectional view taken on the line 6—6 of Fig. 4.

Referring specifically to the drawings, my invention in its present embodiment comprises a lower body, designated generally at A, having the conventional triangular form of a flatiron, and comprising a rim or frame 15 formed on two of its lower edges with a tongue 16 which is co-extensive in length therewith.

The frame 15 is spanned at its bottom by a shoe plate 17 of triangular shape, and formed at its side edges with an upwardly extending flange 18 which is bent to form a groove or channel in which the tongue 16 is adapted to be received for securing the plate to the frame. Additional securing means may be provided in the form of screws 20 extending through the flange and into the tongue. This plate 17 is formed with a multiplicity of downwardly directed apertures 21 through which steam is adapted to be emitted as will be later described. The upper edge of the frame 15 is provided with a continuous lip 22, the function of which will be later described.

The flatiron also includes an upper body designated generally at B, made in sections separable one from the other to facilitate assembly and disassembly for purposes of cleaning and repair. It comprises a carrying section 25 which is of triangular cupped form and of an area to be freely movable vertically in the frame 15 to occupy lowered and elevated positions, as will be later described herein.

This carrying section includes a triangular rim 26, spanned at its lower edge by a bottom wall 27 which is integral therewith. On the outer side of this wall is a continuous lip 28 which is adapted to abut the lip 22 when the carrying section is in its uppermost position, thus defining the elevated position of such section.

Within the carrying section are posts 29 integral with the bottom wall 27 and connected by rods 29a formed of electrical insulating material. About these rods is coiled an electrical heating element 30 in the form of a flat metal strip connected at its ends to wires 31 contained in a flexible cable 32 which is adapted for connection to a source of current.

A member 33 is fixed to and rises centrally from the bottom wall 27, and it is bored to provide a passage 34 which leads downwardly to a perforated disk 35 suitably secured in the lower end of the member. Adjacent its upper end the member is formed exteriorly with an annular collar 36.

Formed on the inner side of the rim 26 is a continuous lip 37 which provides a support for a plate 38 of triangular form. This plate is provided with an opening 39 through which the upper end of the member 33 extends. A tray 40 of triangular form is supported on the plate 38, and it is provided with a collared opening 41 through which the upper end of the member 33 extends so that the passage 34 is placed in communication with the interior of the tray. A gasket 42 is interposed between the tray and the collar 36 to form a steam-tight joint between the tray and the member.

The upper body B also includes a cover section 43 of triangular form, and including a top wall 44 and a depending flange 45, through which screws 46 extend for securing the section to the rim 26 of the carrying section. Suitable openings are provided in the cover section and the plate 38 through which the cable 32 may be extended from the heating element 30. The area of the cover section is such that the flange 45 will abut the upper edge of the frame 15 when the upper body is in its lowermost position as shown in Fig. 2, so as to leave the wall 27 slightly spaced from the shoe plate 17 in order that steam may be free to flow from the perforations in the disk 35 and then outwardly of the apertures 21.

With the cover section secured on the carrying section as above described, the wall 44 serves as a closure for the top of the tray 40 to form a steam receiving chamber S, the joint between the wall and the upper edge of the tray being sealed by a gasket 47. Steam is adapted to be supplied to the chamber S from any suitable source such as a boiler located at some remote point and connected to the flatiron through a flexible pipe 48.

As best shown in Fig. 6, this pipe 48 is connected with a nozzle 49 carried by a casing 50. This casing is mounted on the wall 44 by means of a head 51 which is screw-threaded into the wall. This head is formed integral with the cas-

ing and the interior of the head provides a seat 52 for a valve 53. The valve is carried by a stem 54 movable axially in the casing and through a guide flange 55. The upper end of the stem projects from the casing for manual operation to open the valve against the tension of a spring 56 arranged about the stem and between the flange 55 and a shoulder 57 on the stem.

When the valve is open steam from the pipe 48 can pass downwardly through the casing 50 and into the chamber S to flow downwardly through the passage 34 and outwardly through the sole plate, as will be more fully described hereinafter. To reduce the possibility of con-

den-sation of the steam in its passage to the chamber S, both the seat 52 and the valve 53 are made in stepped form as illustrated. Such form gives them greater surface area so that when the two become heated by the steam, con-

den-sation of the steam is reduced to a minimum.

The upper body B is urged to the elevated position shown in Fig. 3 by the provision of two or more springs 58 which are disposed exteriorly of the bodies A and B so that they are remotely dis-

posed with respect to the heating element 30 as well as the steam chamber S. Thus they are not subject to the intense heat of either and, as a consequence, their tension is preserved to urge the upper body to elevated position as intended.

The springs 58 are mounted on rods 59, secured at their lower ends in the bottom of cups 60 depending from ears 61 fixed to the outer sides of the frame 15. Sleeves 62 telescope within the cups 60 and receive both the rods and the springs.

The upper ends of these sleeves are closed and extend through ears 63 formed on the cover sec-

tion 43, collars 64 being fixed on the sleeves to limit movement of the latter upwardly through the ears.

When and as desired in the use of the flatiron, the upper body B is adapted to be secured in its lowermost position and against the tension of the springs 58 by means of a latch bar 65, pivoted on the top of the wall 44 by a screw 66. By means of a knob 67, the bar 65 can be rotated so that its ends engage or disengage keepers 68 formed on the upper ends of flat rods 69 secured by screws 70 to the frame 15.

For the purpose of manipulating the flatiron as well as to depress the upper body B to its lowermost position, a conventional handle 71 is secured at its ends in sockets 72 in the wall 44 by means of screws 73.

In the use of my flatiron, assuming that the cable 32 is connected to a source of current, and the pipe 48 to a source of steam, downward pressure on the stem 54 opens the valve 53 to supply steam to the chamber S where it collects and then flows through the passage 34, the perforated disk 35 and then outwardly through the apertures 21 and against the fabric being ironed. Due to the intimate association of the heating element 30 with the chamber S and the passage 34, the heat emanating therefrom raises the tem-

perature of the steam so that when discharged through the sole plate it is superheated to attain the rapid steaming and pressing of a fabric and in such manner as to leave the fabric substantially devoid of moisture.

These results are better produced when the upper body B is depressed to the lowered position shown in Fig. 2, since the superheated steam quickly reaches the sole plate, and the heating element is close to the fabric to assist in rapid drying of the fabric as it is being pressed.

Depressing and holding the body B in lowered position is easily effected by pressing down on the handle 71, and since the combined tension of the springs 58 only slightly exceeds the weight of the body, only a light downward pressure is necessary to maintain it depressed. When the handle is relieved of downward pressure the springs force the body B upwardly to the elevated position shown in Fig. 3, wherein the heating element 30 is spaced sufficiently from the shoe plate 17 to eliminate all danger of scorching or burning the fabric being ironed. This avoids the necessity of lifting the flatiron from the fabric and placing it on a stand between ironing operations, and when the operator is not ironing he naturally releases the stem 54 to allow the valve 53 to close, thus discontinuing steam supply to the flatiron.

If a prolonged ironing operation is to be performed the operator first forces the upper body B to lowered position, and then actuates the latch bar 65 to engage the keepers 68, when the body will be maintained in lowered position.

The convenient position of the valve stem 54 in relation to the handle 71 provides instant control of steam supply to the flatiron in steaming a fabric when and as required, and whether or not the heating element 30 is contiguous to the shoe plate.

Although I have herein shown and described only one form of flatiron embodying my invention, it is understood that various changes and modifications may be made herein without departing from the spirit of my invention and the spirit and scope of the appended claims.

What I claim is:

1. A flatiron including: a lower body having an apertured sole plate; an upper body having a steam receiving chamber therein, and a passage leading from the latter to the bottom of the lower body; an electrical heating element carried by the upper body; the lower body being hollow so as to receive the upper body in telescoping relation therewith to occupy an elevated position in which it is sufficiently spaced from the sole plate to prevent the heat radiated from said element from scorching or burning the material being ironed, and a lowered position in which said element is contiguous to the sole plate; and springs disposed exteriorly of both bodies and operatively associated therewith for urging the upper body to elevated position in the lower body and coacting means on both bodies to determine the elevated position.

2. A flatiron including: a lower body having an apertured sole plate; an upper body having a steam receiving chamber therein, and a passage leading from the latter to the bottom of the lower body; an electrical heating element carried by the upper body; the lower body being hollow so as to receive the upper body in telescoping relation therewith to occupy an elevated position in which it is sufficiently spaced from the sole plate to prevent the heat radiated from said element from scorching or burning the material being ironed, and a lowered position in which said element is contiguous to the sole plate; springs disposed exteriorly of both bodies and operatively associated therewith for urging the upper body to elevated position in the lower body; coacting means on both bodies to determine the elevated position and means for latching the upper body in lowered position against the tension of the springs.

3. A flatiron having a lower body including a

sole plate with downward directed apertures therein; an upper body, the lower body being hollow so as to receive the upper body in telescoping relation therewith to occupy lowered and elevated positions therein; a chamber in the upper body; a flexible pipe communicating with the chamber for supplying steam thereto from a remote source; a passage within the upper body leading from the chamber to and through the bottom thereof to discharge steam into the lower body for final discharge through said apertures; means exteriorly of said bodies and operatively associated therewith for urging the upper body to an elevated position in the lower body; and coacting members on said bodies for defining the elevated position of the upper body.

4. A flatiron having a lower body including a sole plate with downward directed apertures therein; an upper body, the lower body being hollow so as to receive the upper body in telescoping relation therewith to occupy lowered and elevated positions therein; a chamber in the upper body; a flexible pipe communicating with the chamber for supplying steam thereto from a remote source; a passage within the upper body leading from the chamber to and through the bottom thereof to discharge steam into the lower body for final discharge through said apertures; means exteriorly of said bodies and operatively associated therewith for urging the upper body to an elevated position in the lower body; an electrical heating element in the upper body below said chamber and about said passage; and coacting members on said bodies for defining the elevated position of the upper body.

5. A flatiron including: a lower body which is hollow; an apertured sole plate; a connection between said plate and said body; an upper body comprising a carrying section of cup form telescopically fitted in the lower section to occupy lowered and elevated positions therein; a tubular member fixed to and rising from the bottom of said section, and providing a passage downwardly through the section; a plate fitted within said section; an electrical heating element in said section beneath said plate and around said member; a tray supported on said plate and into which the upper end of said member extends; a cover section secured to the carrying section and closing the top of said tray to coact therewith in forming a chamber; a valve in the cover section for controlling the supply of steam to the chamber from an exterior source; and means exteriorly on the lower body and the cover section for urging the carrying section to elevated position.
